UNITED STATES PATENT OFFICE.

EARL J. MEYBERG, OF LOS ANGELES, CALIFORNIA.

DESIGN FOR A WALL LIGHTING FIXTURE.

Application filed November 24, 1925. Serial No. 15 532. Term of patent 14 years.

To all whom it may concern:

Be it known that I, EARL J. MEYBERG, a citizen of the United States, residing at Los Angeles, in the county of Los Angeles and State of California, have invented a new, original, and ornamental Design for a Wall Lighting Fixture, of which the following is a specification, reference being had to the accompanying drawing, forming a part thereof:

Fig. 1 is a front elevation of the wall lighting fixture.

Fig. 2 is a side elevation of the same.

I claim:

The ornamental design for a wall lighting fixture, as shown.

EARL J. MEYBERG.
